UNITED STATES PATENT OFFICE.

WILLIAM H. BIXBY, OF WATERLOO, IOWA.

CROSSING-SIGNAL FOR RAILWAY-TRACKS.

1,332,705.

Specification of Letters Patent.

Patented Mar. 2, 1920.

Application filed August 13, 1919. Serial No. 317,263.

To all whom it may concern:

Be it known that I, WILLIAM H. BIXBY, a citizen of the United States, residing at Waterloo, in the county of Blackhawk and State of Iowa, have invented certain new and useful Improvements in Crossing-Signals for Railway-Tracks, of which the following is a specification, reference being had to the accompanying drawings.

10 This invention relates to signals designed to be disposed at the intersection of a public road with a railway track for the purpose of indicating the approach of a train to the crossing, and particularly to that 15 class of signals wherein a semaphore arm is provided which is shifted upon the approach of a train to a safety or danger indicating position.

The general object of my invention is to 20 provide a very simple and effective mechanism of this character including a semaphore arm, and means actuated by an approaching train whereby the semaphore arm may be shifted to its cautionary or danger position, and whereby after the train has reached the crossing, the signal arm may be automatically shifted to its safety 25 position.

A further object is to provide a construction of this kind in which a dash pot is used for the purpose of controlling the movements of the semaphore or signal arm and preventing too rapid movement of the semaphore.

30 And a further object is to provide a semaphore which is held in its safety indicating position by a trip, this trip being tripped by a member carried on a locomotive, the semaphore then shifting automatically 35 to its danger position and remaining so shifted until the train reaches the crossing and is about to pass it, whereupon the member on the engine will automatically 40 act to reset the semaphore to its safety position, wherein it is again locked by said trip.

45 Other objects will appear in the course of the following description.

My invention is illustrated in the accompanying drawings, wherein:

50 Figure 1 is a side elevation of a crossing signal constructed in accordance with my invention;

Fig. 2 is a top plan view of the construction shown in Fig. 1;

Fig. 3 is a vertical sectional view of the 55 signal standard and semaphore;

Fig. 4 is a longitudinal detail sectional view of the signal actuating device and guide, showing the actuating means on the locomotive;

Fig. 5 is a section on the line 5—5 of Fig. 3;

Fig. 6 is a section on the line 6—6 of Fig. 4;

Fig. 7 is a sectional view of the plunger 65 or piston;

Fig. 8 is a sectional view of the trip 34 and 34;

Fig. 9 is a longitudinal sectional view of the slide frame 23 and of the slide;

Fig. 10 is a section on the line 10—10 of Fig. 9.

Referring to these figures, it will be seen that my signal comprises essentially a vertical frame work, designated generally 10, 75 disposed to one side of the intersection of a public road with the tracks of a railway, this vertical frame being approximately square in cross section, though it may be circular, and this frame may be either solid 80 or skeletal in form as desired, under all circumstances provided with vertical guide bars 11 within which is mounted a vertical slide 12 pivoted to the rear end of a semaphore or signal arm 13, the extremity of 85 which may carry any desired signal, such as a flag, a placard, a light, or other obvious device, and which is preferably weighted. Extending from the frame 10 is a bracket 14 upon which the lower end of a link 15 90 is pivoted, the upper end of this link being pivotally connected to the semaphore arm 13, at 16. It will be obvious now that upon a descent of the slide 12, the arm 13 will be raised and upon an ascent of the slide 12, 95 the arm will be lowered to a horizontal position when the slide 12 reaches the upper end of the frame. Disposed within the frame 10 at the lower portion thereof is a cylinder 17, within which operates a piston 18 provided with apertures controlled by valves 19 and 20. The valve 20 opens to allow the passage of air or other fluid through the piston upon the down stroke of the piston, while the valve 19 opens upon the up stroke of the piston to allow the passage of oil or other liquid. This piston is connected to a piston rod 21, passing out through a

stuffing box 22 in the upper end of the cylinder and pivotally connected at its upper end to the slide 12.

For the purpose of releasing the sliding block 12 upon the approach of a train on the tracks A, I provide between the rails *a* of the track a longitudinally extending slide frame 23, having overhanging flanges, and dispose within this frame the longitudinally movable slide 24, which is formed of two parts as will be later described and has free, sliding movement within the frame and projects out between the flanges of the frame 23. The upper portion of this slide above the frame extends upward to a height somewhat greater than the height of the rails *a*. A cable 25 is attached to the slide 12 and extends downward through the frame 10 and passes over a pulley 26, thence to the middle of the track A, over a pulley 27, and is attached to a coiled, contractile spring 28. From this spring a cable 29 extends longitudinally through the lower portion of the frame 23 around the pulleys 30, and then is attached to the slide 24. It will thus be seen that when the slide 24 is struck by a train and shifted longitudinally toward the left in Fig. 1, it will pull on the cable 29. This will stretch the spring 28, and when this spring has been stretched a certain distance, the cable 25 will be pulled, drawing the slide 12 downward from the position shown in full lines to that shown in dotted lines in Fig. 3. At its forward end, the side rails of the slide frame 23 are downwardly turned, as at 31, so that when the slide 24 reaches the forward end of the slide frame, it will move downward and out of the path of movement of the actuating device on the pilot of the engine. It is held in this position by a latch 32 of any suitable character, which is preferably a resilient latch and which will yield to permit the passage of the slide 24 and then spring upward to hold the slide from reverse movement on the slide frame 23. Attached to this latch is a cable 33 which extends along the track, and is connected to a trip 34, this trip being disposed at any suitable distance in advance of the crossing.

For the purpose of actuating the trip and of afterward resetting the slide 24, as will be hereinafter explained, I attach to the pilot 36 of the locomotive an angle bar 37 extending transversely of the track, disposed above the middle thereof, and having a downwardly extending flange which will strike the trip 34 to thereby trip the slide 24, and which will also shift the slide 24 longitudinally along the slide frame until the slide 24 moves downward over the curved end of the slide frame and out of the way of the angle bar. Preferably, the trip 34 is formed in two sections, one of the sections constituting the body of the trip, and the other

35 a pivoted extension of the body which will move with the body in the direction of the arrow in Fig. 8, but which will trip over independently of the body when a train is backing or when a train passes in the 70 opposite direction.

The operation of this device is as follows: Normally, the semaphore arm 13 is disposed in the dotted line position in Fig. 3. The block 12 is pulled down to its farthest extent, and as a consequence the slide 24 will be in the dotted line position shown in Fig. 4. The weight of the semaphore arm 13 will tend to carry the slide back to the full line position in Fig. 4. Now when the 80 train approaches the station, the angle bar 37 will strike the extension 35 of trip 34, and rock the trip 34 in the direction of the arrow in Fig. 8, thus releasing the detent or latch 32. This permits the semaphore arm, which 85 is preferably weighted, to drop to the full line position shown in Figs. 1 and 3, and this of course, draws the slide 24 back to the full line position shown in Fig. 3. When the train reaches the crossing, the angle bar 37 90 will strike slide 24 and cause a movement of the slide along the slide frame, which will lift the semaphore arm, and this movement will continue until the slide 24 passes over the curve at the end of track 23 and is again 95 caught by the latch 32. The parts are thus automatically reset.

The impact between the angle bar 37 and the slide 24 is cushioned or taken up by the coiled spring 28, this coiled spring being 100 about three feet long. As soon as the spring has stretched a certain amount, it will commence to exert a pull upon the cable 25 and this will draw down on the slide 12, as before explained, raising the signal arm to its safety 105 position. The liquid within the chamber or cylinder 17 yieldingly resists the movement of the sliding block 12 in either direction, thus preventing too quick a drop of the semaphore arm or too violent a lifting movement. Preferably, the liquid contained in the cylinder 17 will be oil, which is not liable 110 to freeze.

While I do not wish to be limited to the particular construction of the slide 24, I 115 preferably so form this slide that if by any chance the latch 32 fails to work, the part of the slide 24 that is above the rails can be pushed down out of the way when a train comes in the opposite direction and then returned to its normal position. To this end, I have formed the slide 24 of an outer body longitudinally slotted in its top for a portion of its length, and disposed within the outer body 24 is a T-shaped member 24^a having an upwardly inclined face and a tang which is pivoted, at 24^b, to member 24. Springs 24^c urge this member 24^a upward but permit its downward movement when the member 37 on the cow catcher strikes the 125 130

inclined face of member 24. The operation of this device is obvious and needs no further description.

I have illustrated my device as applied to 5 a single track and have assumed that the traffic is all in one direction. Where, however, traffic is in opposite directions, two of these devices should be installed, one being operated by a movement of trains in one direction and the other by a movement of trains in the opposite direction. It will be seen that 10 my invention is very simple, and that it is thoroughly effective for the purpose intended. The connecting cables may be of any 15 desired length so as to cause an actuation of the arm by the train when the train is any desired distance from the crossing. It will be obvious that my invention does away with the necessity of keeping a flagman at crossings 20 and that by giving the signal of the approach of a train, it will prevent accidents by warning automobiles, drivers, and other of the approach of a train.

I claim:—

25 1. A crossing signal of the character described comprising a vertical frame, a vertically movable slide mounted in the frame, a signal arm having its rear end pivoted to the slide and being pivotally supported outward 30 of the frame, a dash pot to which the slide is connected operating to cushion the movement of the slide in either direction, a longitudinally movable slide mounted between the rails of a track and adapted to be engaged 35 by an actuating device on a train, a cable connecting the first and second named slides to cause a vertical movement of the first named slide upon a longitudinal movement of the second slide, a coiled contractile 40 spring disposed in the length of the cable and adapted to take up shock, a latch adapted to engage the second named slide when it has been shifted to its full extent in one direction to hold it from reverse movement, 45 and means for releasing the latch.

2. A crossing signal of the character described comprising a vertical frame, a vertically movable slide mounted in the frame, a signal arm having its rear end pivoted to the slide and being pivotally supported outward 50 of the frame, a dash pot to which the slide is connected operating to cushion the movement of the slide in either direction, a longitudinally movable slide mounted between the rails of a track and adapted to be engaged 55 by an actuating device on a train, a cable connecting the first and second named slides to cause a vertical movement of the first named slide upon a longitudinal movement of the second slide, a coiled contractile 60 spring disposed in the length of the cable and adapted to take up shock, a latch adapted to engage the second named slide when it has been shifted to its full extent in one direction to hold it from reverse movement, 65

and means for releasing the latch including a trip mounted between the rails of the track and operatively connected to the latch to cause its release when the trip is struck by the actuating device on the train.

3. A crossing signal of the character described comprising a semaphore arm pivoted for movement into or out of a horizontal and danger indicating position and urged toward such horizontal position, a sliding member mounted between the tracks and adapted to be engaged by a train and to be shifted longitudinally thereby, said sliding member being operatively engaged with the semaphore arm to cause it to rise when the sliding member is shifted by a train, a latch disposed in the path of movement of the sliding member and engaging with and holding said sliding member in its shifted position, and a trip device disposed in advance of said sliding member and operatively connected to the latch and adapted to be engaged by a train to release said latch and to release the sliding member to thereby cause the semaphore arm to descend to its horizontal position.

4. The combination with a railroad track, of a vertically movable member disposed beside the track and urged to a lowered position, a sliding member mounted between the rails of the track for movement parallel thereto and adapted to be engaged by a train and to be shifted longitudinally thereby, said sliding member being operatively engaged with said vertically movable member to cause the vertically movable member to rise when the sliding member is shifted in one direction by a train, a latch engaging with the sliding member and holding the sliding member in its last named shifted position, and a trip device disposed in advance of said sliding member and operatively connected to the latch and adapted to be engaged by a train to release the latch, and thereby release the sliding member to thereby cause said vertically movable member to descend to its first stated position.

5. A crossing signal comprising a semaphore arm pivoted for movement into or out of a horizontal, danger indicating position and urged toward this position, means for holding the semaphore arm out of its horizontal position including a longitudinally extending guideway disposed between the tracks, the forward portion of the guideway being downwardly turned, a slide mounted on this guideway and adapted to be shifted therewith by a train in one direction, a cable connection between the slide and the semaphore arm to cause the semaphore arm to be raised to a safety position when the slide has been shifted longitudinally along this guideway to the downwardly curved end of the guideway, a latch normally holding the slide in the last named position, a

cable extending from the latch to a position in advance of the guideway, and a train actuated trip disposed between the tracks and operatively connected to the latch to cause its release when struck by a train.

6. A crossing signal of the character described comprising a vertical frame disposed adjacent the crossing, a vertically movable, sliding block mounted therein, a signal arm pivoted to the block to be shifted therewith into or out of operative position, the arm being urged by gravity to a horizontal, danger indicating position, a longitudinally movable slide disposed between the rails of the track, a longitudinally extending frame disposed between the rails of the track and on which said slide is mounted, the slide projecting above the rails of the track and adapted to be engaged by an actuating device on the train, a cable extending from the sliding block to the track and connected to the slide mounted on said guideway, there being pulleys guiding said cable, a coiled spring disposed in the length of the cable to take up shock, one extremity of the slide frame between the track being depressed to permit the slide to move out of the way of the actuating device on the train, a latch at this depressed end engageable with the slide to prevent its retraction, and a trip mounted on the track in advance of the crossing and operatively connected to said latch to cause its release when the trip is struck by a train whereby the semaphore arm may be initially released by an approaching train to permit it to shift to its danger indicating position and then will be raised when the train has reached the crossing through the operation of said slide and will be held in its raised position after the train has passed by means of the latch.

7. A crossing signal of the character de-

scribed comprising a semaphore arm pivoted for movement to a raised or to a horizontal and danger indicating position and urged toward said horizontal position, a sliding member mounted between the tracks and adapted to be engaged by a train moving in one direction and shifted longitudinally by the train but yielding downward upon the engagement therewith of a train moving in the opposite direction, said sliding member being operatively engaged with the semaphore arm to cause it to rise when the sliding member is shifted by a train, a latch in the path of movement of said sliding member, said latch engaging and holding it in its shifted position, and a trip device disposed in advance of said sliding member and operatively connected to the latch and adapted to be engaged by a train to release the latch from its engagement with the sliding member to thereby release the sliding member and cause the semaphore arm to descend to its horizontal position.

8. In a device of the character described, a tripping device comprising guides having overhanging flanges, a hollow member disposed between said guides and having a longitudinal slot, and a T-shaped body having a beveled upper face disposed in said hollow member and projecting through the slot, this body being pivoted at one end to the hollow member or casing, and a spring urging the opposite end of the body upward to project out of said slot.

In testimony whereof I hereunto affix my signature in the presence of two witnesses.

WILLIAM H. BIXBY.
